Primary Examiner — Derrick Holland*Assistant Examiner* — Jennifer O King*(74) Attorney, Agent, or Firm* — The Webb Law Firm(57) **CLAIM**

The ornamental design for a transducer, as shown and described.

DESCRIPTION

FIG. 1 is an upper perspective view of a transducer, showing my new design;

FIG. 2 is a front view thereof;

FIG. 3 is a right side view thereof;

FIG. 4 is a rear view thereof;

FIG. 5 is a left side view thereof;

FIG. 6 is a top view thereof;

FIG. 7 is a bottom view thereof; and,

FIG. 8 is a cross-sectional side view thereof, taken along line **8-8** of FIG. 2.

The broken lines shown represent unclaimed subject matter and form no part of the claimed design.

1 Claim, 4 Drawing Sheets**FIG. 1**

FIG. 2**FIG. 3****FIG. 6**

FIG. 4**FIG. 5****FIG. 7**

FIG. 8
